(57) CLAIM

The ornamental design for an adjustable height pet feeder, as shown and described.

DESCRIPTION

FIG. 1 is an exploded perspective view of an adjustable height pet feeder showing my new design;

FIG. 2 is a front elevation view with the opposite side being identical thereto;

FIG. 3 is a side elevation view with the opposite side being identical thereto;

FIG. 4 is a top plan view thereof;

FIG. 5 is a bottom plan view thereof;

FIG. 6 is an enlarged perspective view of the shim support element (as seen in FIG. 12) shown separately for clarity of disclosure;

FIG. 7 is a top plan view of the shim element;

FIG. 8 is a bottom plan view of the shim element;

FIG. 9 is a side plan view of the shim element;

FIG. 10 is a side plan view of the shim element opposite to the side plan view of FIG. 9;

FIG. 11 is a longitudinal view of the shim element; and,

FIG. 12 is a perspective view of the top inverted to illustrate the shim element housed on the underside of the top.
